UNITED STATES PATENT OFFICE.

FREDERICK W. DUNTON, OF HOLLIS, NEW YORK, ASSIGNOR TO EMILY M. DUNTON, OF SAME PLACE.

SINGLE-RAIL-RAILWAY CAR.

SPECIFICATION forming part of Letters Patent No. 592,866, dated November 2, 1897.

Application filed July 29, 1897. Serial No. 646,288. (No model.)

To all whom it may concern:

Be it known that I, FREDERICK W. DUNTON, a citizen of the United States, and a resident of Hollis, in the county of Queens and State 5 of New York, have invented certain new and useful Improvements in Single-Rail-Railway Cars, of which the following is a specification.

This invention relates to a railway-car of the class which travels on a single bottom rail 10 and is sustained by means of a single overhead guide-rail.

The invention is designed more particularly to impart motion to such car in a simple, direct, and efficient manner by a motor which 15 is supported by the car-truck and is coupled to the traction-wheel by direct gear.

In the accompanying drawings, Figure 1 is a side elevation, partly in section, of a railway-car embodying my invention; Fig. 2, an enlarged sectional side view of the truck, and 20 Fig. 3 a sectional plan thereof.

The letter A represents the body of the car, which is supported at each end by a truck consisting, essentially, of a square frame a, the two longitudinal sides of which are provided with boxes a' to receive the axle b of the traction-wheel c. The car-body is so mounted upon the truck that the latter has a free rotary motion, and to this effect the car- 25 body is provided with a pair of spring-supported beams d, having segmental corner-plates d', that are engaged on their lower sides by antifriction-rolls a², journaled in the corners of frame a. A second set of rolls d², hung 30 to the beams d on vertical axes and engaging curved corner-plates a³ of frame a, constitute in effect a fifth-wheel that permits free rotary motion of the truck.

In order to guide the car along the upper 35 rail B of the track, the frame a is provided with an upwardly-extending yoke e, which projects through and above the car-body and

carries at its top the guide-rolls e', which engage the sides of the upper rail. All this is more fully described in Patent No. 562,218, 45 granted to me June 16, 1896.

To the end rails of frame a there is attached, at a short distance from one of its side rails, a longitudinal beam f, which constitutes the support for one end of an electric motor g, 50 the other end of which is supported by one of the side rails. The axle g' of this motor is placed parallel to the wheel-axle b and within the periphery of the traction-wheel c. This wheel is provided with an internal circumferential gear c', engaged by a pinion g², mounted upon the motor-axle g'. Thus motion is transmitted from the motor-axle to the traction-wheel by direct gear, and as all the parts are supported upon the truck-frame their relative 55 position will remain undisturbed, without regard to the relative position between truck and car-body.

It will be seen that in my improved railway-car the traction-wheel is centered within the 65 fifth-wheel and is directly intergeared with the motor. In this way freedom of motion for the truck is insured and a compact connection between traction-wheel and motor is effected.

What I claim is—

In a single-rail-railway car the combination of a traction-wheel having an internal gear with an electric motor having a pinion that engages such wheel, a supporting-frame, and with a fifth-wheel within which the traction-wheel is centered, substantially as specified. 75

Signed at New York, in the county of New York and State of New York, this 26th day of July, A. D. 1897.

FREDERICK W. DUNTON.
